UNITED STATES PATENT OFFICE.

FRANK E. GETTS, OF CHICAGO, ILLINOIS, ASSIGNOR TO ELECTRICAL ENGINEERS EQUIPMENT COMPANY, OF CHICAGO, ILLINOIS, A CORPORATION OF ILLINOIS.

BUS-BAR INSULATOR AND SUPPORT.

1,233,568.

Specification of Letters Patent.

Patented July 17, 1917.

Application filed July 31, 1916. Serial No. 112,236.

To all whom it may concern:

Be it known that I, FRANK E. GETTS, a citizen of the United States, residing at Chicago, in the county of Cook and State of Illinois, have invented a certain new and useful Improvement in Bus-Bar Insulators and Supports, of which the following is a full, clear, concise, and exact description, reference being had to the accompanying drawings, forming a part of this specification.

My invention relates to busbar insulators and supports.

In the construction of switching and distributing boards it is necessary to carry common busbars to a number of points upon the insulating board or slab in such manner as to secure complete insulation from the grounded framework or other supporting means, and at the same time secure good mechanical support to insure permanence and security.

The object of the present invention is to provide an insulating support such as may be employed for supporting busbars or the like. One particular point of novelty which I wish to emphasize is the use of an internal reinforcing member for the porcelain or other friable material which constitutes the body of insulation.

Other features of novelty will be apparent to those skilled in the art from the following description.

In the accompanying drawings in which I have illustrated one modification of my invention—

Figure 1 is a front elevation with parts broken away; and

Fig. 2 is a plan view of the same.

The device which I have shown comprises essentially a body of insulation 1, which is provided with a corrugated surface in order to make the creepage distance greater. This body 1 forms the insulator proper and in general contour is a cylinder or frustum of a cone having an upper flat radial base 2 and a lower flat radial face 3. The insulator 1 is provided with an axial recess 4 the interior surface of which is provided with suitable corrugations 5 which permits the cementitious or binding material 6 to insure a firm grip upon the interior surface of the recess. The insulator 1 seats upon a base plate 7. The base plate 7 is provided with a flat bottom to permit it to seat solidly

upon any plane support. Lugs 8 are formed integral with the base plate 7 and these lugs placed at equi-distant points, are adapted to be engaged by suitable bolts 9 for holding the device in position. The top of the base plate 7 is provided with a flat radial surface 10 which is adapted to engage the flat radial surface 3 of the insulator 1. The base plate 7 is cored out as shown in Fig. 1, leaving however the axial boss 11 which is screw threaded to receive a short section of rod 12 that projects up into the cavity or recess 4 in the insulator 1. The rod 12 is provided with peripheral notches 13 for permitting the cementitious material 6 to secure a firmer hold upon the same.

The lower part of the insulator is provided with a groove 14 adjacent the radial face 3 and in a similar manner the base plate 7 is provided with a peripheral groove 15. A split clamp 16, which embraces the adjacent edges of the two parts, has suitable flanges fitting into the grooves 14 and 15 serving to clamp the two parts together. A filling of cement 17 or the like may be employed between the adjacent parts and the split clamps 16.

A metal supporting block 18 rests upon the top face of the insulator 1 and is held in position by means of a split clamp 19 which has flanges seating in the grooves 20 and 21 for holding these two parts firmly in engagement. The clamping block 18 is provided with symmetrically projecting ears or lugs 22 shown in this particular case as four in number. A clamping member 23 of generally rectangular form is provided with suitable lugs 24 which register with the lugs 22 and form suitable means for reception of the bolts 25 which hold the clamp and block together. The flat busbar 26 is gripped between the clamp 23 and the block 18 by means of these bolts. It is obvious that the busbar 26 can be passed between the clamp 23 and the block 18 in a direction at right angles to that shown in Figs. 1 and 2, or in fact two busbars may be crossed under the clamps 23.

The assembly of the device is as follows:

The insulator 1 is turned so that the recess 4 faces upward and a quantity of neat cement is poured into this recess. The base plate 1 with the short length of rod 12 secured to it, is then laid against the bottom of the insulator with the rod embedded in the

cement. The split clamp 16 is opened at the bolts 27 and a preparation known in the market as smooth-on is applied to the inner surface of the clamps 16. It is a characteristic of the composition above mentioned, namely, smooth-on, that when the same is allowed to set and harden, particularly in contact with iron or other metals, it forms a very close union between the parts and becomes in fact integral by a sort of molecular union. In a similar manner the clamp 19 is opened, smeared with smooth-on and then applied and clamped against the adjacent parts to hold them firmly in position.

15 While I have described my invention with considerable particularity, I wish it to be understood that I do not intend to be limited to the precise and specific details of construction except as the same are set forth 20 in the appended claims, as I consider the device capable of modification and variation in proportions and dimensions.

I claim:

1. In combination a circular base plate 25 having a flat radial face, a reinforcing projection extending axially from said face, a body of insulation having a radial face and having an axial recess for receiving said reinforced projection, said body of insulation 30 having a peripheral groove adjacent said radial face and said base plate having a similar peripheral groove adjacent its radial face and an encircling clamp having portions adapted to lie in said grooves to clamp 35 said body and said base plate together.
2. In combination, a circular base plate having a flat radial face, said base plate having means for clamping the same to a support, a reinforcing projection extending axially 40 from said face, said projection comprising a short rod screwed into said base plate, said rod having notches cut in the side wall thereof, a body of insulation having a radial face and an axial recess for receiving said 45 reinforcing rod, the interior face of said recess being roughened, a filling of cementitious material between the walls of said recess and said rod, said body of insulation having a peripheral groove adjacent said 50 radial face and said base plate having a similar peripheral groove adjacent its radial

face, and an encircling clamp having portions adapted to lie in said grooves to clamp said body and base plate together.

3. In combination, a base having a plane 55 radial face provided with an axial projection, an insulating body having a radial face provided with an axial opening to receive said projection, said projection and opening having annular recesses to serve as holding 60 means for cement or the like, said base plate and insulating body having annular grooves adjacent their adjoining faces and clamping means engageable with said grooves to reinforce the insulator.

4. In combination, an insulating conductor support comprising a non-conducting body having a recess therein, a base plate having a reinforcing projection to seat in said recess, a conductor block carried by 70 the body, said body, plate and conductor block having peripheral grooves and a plurality of clamping elements having flanges to engage in said grooves and rigidly connect said body, plate and conductor block.

5. In combination, an insulating conductor support comprising a base plate having a peripheral groove and a reinforcing projection, an insulating supporting body having a plurality of parallel peripheral grooves 80 along the outer face thereof and a longitudinal recess to receive said projection, a conductor block receivable on the free end of said body, and provided with a peripheral groove, means to secure a conductor to said block, and a pair of clamping members having flanges engageable in the peripheral grooves in said body, face plate and conductor block.

6. In combination, a conductor support 90 comprising a base plate, a non-conducting body having peripheral grooves and a longitudinal recess opening at one end thereof, said base plate having a reinforcing column to engage in said recess, a conductor block, 95 having a peripheral groove, and clamping means to engage the grooves in said base plate and clamping block and the endmost grooves of said insulating body.

In witness whereof, I hereunto subscribe 100 my name this 25th day of July, A. D. 1916.

FRANK E. GETTS.
